US0D1042096S

(12) **United States Design Patent** (10) Patent No.: **US D1,042,096 S**
(45) Date of Patent: ** Sep. 17, 2024

(54) **CABLE ORGANIZER**

(71) Applicant: **Crestron Electronics, Inc.**, Rockleigh, NJ (US)

(72) Inventors: **Sae Jhun**, Bayside, NY (US); **Wendy Feldstein**, Old Tappan, NJ (US); **Ningsheng Zhu**, Whippany, NJ (US)

(73) Assignee: **Crestron Electronics, Inc.**, Rockleigh, NJ (US)

(**) Term: **15 Years**

(21) Appl. No.: **29/819,278**

(22) Filed: **Dec. 14, 2021**

(51) LOC (14) Cl. **09-06**

(52) U.S. Cl.

USPC **D8/356**

(57) **CLAIM**

The ornamental design for a cable organizer, as shown and described.

DESCRIPTION

FIG. 1 shows a top perspective view of a cable organizer with the lid in the closed position according to an embodiment;

FIG. 2 shows a bottom perspective view thereof;

FIG. 3 shows a front elevation view thereof;

FIG. 4 shows a rear elevation view thereof;

FIG. 5 shows a left elevation view thereof;

FIG. 6 shows a right elevation view thereof;

FIG. 7 shows a top plan view thereof;

FIG. 8 shows a bottom plan view thereof;

FIG. 9 shows a top perspective view thereof with the lid in the open position;

FIG. 10 shows a top plan view thereof mounted in a surface with the lid in the closed position and having cables extending therefrom;

FIG. 11 shows a top plan view thereof mounted in a surface with the lid removed and having cables and connectors extending therefrom; and,

FIG. 12 shows a top perspective view thereof mounted in a surface with the lid in the open position.

The broken line portion of the figure drawings is included to show unclaimed subject matter only and forms no part of the claimed design.

1 Claim, 8 Drawing Sheets
